UNITED STATES PATENT OFFICE.

ALFRED F. REILLY, OF ATTLEBORO, MASSACHUSETTS.

DESIGN FOR A COMBINED CIGARETTE LIGHTER AND CIGARETTE CONTAINER.

Application filed January 19, 1928. Serial No. 24,933. Term of patent 3½ years.

To all whom it may concern:

Be it known that I, ALFRED F. REILLY, a citizen of the United States, residing at Attleboro, in the county of Bristol and State of Massachusetts, have invented a new, original, and ornamental Design for Combined Cigarette Lighter and Cigarette Container, of which the following is a specification, reference being had to the accompanying drawing, forming part thereof.

Referring to the drawing,

Fig. 1 is a side view of a combined cigarette lighter and container, showing my new design.

Fig. 2 is a top plan view of the same.

I claim:

The ornamental design for a combined cigarette lighter and cigarette container, as shown.

ALFRED F. REILLY.
